(57) **CLAIM**

The ornamental design for bottle with cap, as shown and described.

DESCRIPTION

FIG. 1 is a front perspective view of one embodiment of a bottle with cap embodying our new design;
FIG. 2 is a front side elevation view thereof;
FIG. 3 is a rear side elevation view thereof;
FIG. 4 is a right side elevation view thereof;
FIG. 5 is a left side elevation view thereof;
FIG. 6 is a top plan view thereof; and,
FIG. 7 is a bottom plan view thereof;
FIG. 8 is a front perspective view of a second embodiment of a bottle with cap embodying our new design;
FIG. 9 is a front side elevation view of the second embodiment;
FIG. 10 is a rear side elevation view of the second embodiment;
FIG. 11 is a right side elevation view of the second embodiment;
FIG. 12 is a left side elevation view of the second embodiment;
FIG. 13 is a top plan view of the second embodiment; and,
FIG. 14 is a bottom plan view of the second embodiment.
The dash broken lines in the drawings define the bounds of the claim and form no part thereof.

1 Claim, 12 Drawing Sheets
